UNITED STATES PATENT OFFICE.

THOMAS SINGLETON, JR., OF NEW BEDFORD, MASSACHUSETTS, ASSIGNOR
TO THE PAIRPONT MANUFACTURING COMPANY, OF SAME PLACE.

DESIGN FOR A GLASS VESSEL.

SPECIFICATION forming part of Design No. 23,761, dated November 6, 1894.

Application filed October 9, 1894. Serial No. 525,434. Term of patent 7 years.

To all whom it may concern:

Be it known that I, THOMAS SINGLETON, Jr., of New Bedford, in the county of Bristol and State of Massachusetts, have invented and produced a new and original Design for a Glass Vessel, of which the following is a specification, reference being had to the accompanying drawings, in which—

Figure 1 is a bottom plan view, and Fig. 2 is a central, sectional elevation.

The leading feature of my design consists in a series of diamond-shaped figures arranged around the vessel, each with its upper point at the bottom of a recess in the rim of the dish, and with one under point well down toward the bottom of the vessel, these large diamond-shaped figures being ornamented by cross-cuts which form small ornamental diamond-shaped heads, and being separated, one from another, by two marginal fan figures whose opposed sides are separated by kite-shaped figures, the longer sides of which converge at the bottom of recesses in the rim of the vessel, while their shorter sides converge between the large diamond-shaped figures, just below the side points thereof and opposite the shorter sides of triangular, grooved figures whose longer sides converge at the bottom of the large diamond-shaped figures, the diverging sides of the triangular grooved figures being opposed to figures composed of grooves extended to the bottom of the vessel.

In the drawings, A are diamond-shaped figures whose upper points a are at the bottom of recesses a' formed in the rim of the vessel. The under points a^2 are well down toward the bottom of the vessel, and each figure A is ornamented by a series of cross-cuts a^3 which produce small diamond-shaped heads a^4 whereby a marked and ornamental appearance is given to each figure A. These figures are arranged around the vessel at a distance apart, being separated by two marginal fan-shaped figures B; a kite-shaped figure D intermediate the figures B, and two grooved, triangular figures F. The longer sides d of the kite-shaped figures converge at the bottom of recesses d' in the rim of the vessel, between the heads b of the figures B, while their shorter sides d^2 converge between the side points a^5 thereof. From the shorter sides d^2 of figures D, the figures F are extended so as to converge at the under points a^2 of figures A. Between the opposed sides of the triangular figures F are fan-shaped figures G which extend well down to the vessel bottom, which is ornamented with a conventionalized star H.

What I claim is—
The design for a glass vessel herein set forth.

THOMAS SINGLETON, JR.
